UNITED STATES PATENT OFFICE.

HENRY C. SCHUMACHER AND WILLIAM A. WINTERS, OF BARBERTON, OHIO, ASSIGNEES
TO THE DIAMOND MATCH COMPANY, OF CHICAGO, ILLINOIS, A CORPORATION OF
ILLINOIS.

MACHINE FOR MAKING MATCH-BOX SHUCKS.

1,270,333.

Specification of Letters Patent. Patented June 25, 1918.

Application filed August 30, 1916. Serial No. 117,610.

To all whom it may concern:

Be it known that we, HENRY C. SCHUMACHER and WILLIAM A. WINTERS, both citizens of the United States, and residents 5 of Barberton, in the county of Summit and State of Ohio, have invented certain new and useful Improvements in Machines for Making Match-Box Shucks, of which the following is a specification.

10 This invention relates to machines for making match-box shucks comprising each a strip of thin veneer bent into appropriate form having its ends overlapped to constitute one of the narrow longitudinal sides of 15 the shuck, and comprising also a thin covering of paper which is glued or pasted to the "tubular" body. In said machines the veneer body of the shuck is formed on a suitable mandrel or forming bar, rectangular in cross-section, and the paper cover, with or without printed matter thereon, is then wrapped about and affixed to such body.

15 The present invention is in the nature of 20 an attachment for shuck machines of the type mentioned; and its object is to provide simple and efficient means whereby in the production of the shuck the proper cross-sectional form of the veneer body is maintained and the paper cover is uniformly applied thereto; thus insuring a product 25 having the requisite structural form, size and appearance.

To this end the invention generally 30 stated comprises means whereby the folded veneer body is accurately positioned on the mandrel or forming bar and whereby the paper cover and the said body are firmly held in close contact during the final folding of the cover flaps.

35 The invention also comprises various features of construction and combinations of parts, all of which will be hereinafter described and claimed.

40 In the annexed drawings—

Figure 1 is a side elevation of a part of a shuck-making machine equipped with positioning and folding mechanism embodying the principle of our invention.

45 Fig. 2 is an end elevation of the same, showing a veneer body with its partially folded cover on the mandrel or forming bar; and indicating in dotted lines the active position of the top pressure member 50 and also the path of the final folding mem-

ber in respect to the projecting ends of the partially folded cover.

Fig. 3 is a perspective view, enlarged, of 50 said body and its partially folded cover, showing a portion of the mandrel in dotted lines.

Figs. 4, 5 and 6 are transverse sections 60 through the mandrel showing the pressure members in active relation to the partially formed shuck, and showing also the final folding member in various positions of operation upon the projecting end flaps of the paper cover.

Fig. 7 is a view illustrating a possible 70 defective condition of the overlapping ends of the veneer body, the occurrence of which my invention is designed to obviate.

Referring to the drawings, 10 designates 75 the usual mandrel or forming bar, rectangular in cross-section, upon which shucks of paper-covered veneer are formed by any usual or approved type of shuck making machine; that is to say, a rectangular sheet of veneer of prescribed size is folded upon the mandrel to produce a body or "skillet" 80 comprising a top *a*, a bottom *b* and two narrow longitudinal sides *c*, *c'* respectively, whereof the side *c* is formed by the overlapping of the end portions of the material; and a sheet of thin paper *d* of proper size, 85 having paste applied to its under surface, is then closely wrapped upon and affixed to the veneer body thus produced, the final folding of the paper being effected by overlapping its ends and pasting them together 90 and to the narrow side *c'* of the veneer body.

The mechanism embodying our invention 95 is associated with the means for accomplishing the final folding of the paper cover, and therefore a preferred form of folder is herein illustrated. This folder comprises a horizontal bar 11 which is so mounted and operated in relation to the adjacent side of the mandrel as to fold in successive order against the veneer body the upper and lower 100 projecting ends flaps *d'*, *d''*, respectively of the paper cover. In the present instance the folder bar 11 is supported on the upper end of an upstanding arm 12 which is pivoted at its lower extremity to the free end of a 105 lever 13 which, in turn, is fulcrumed on a shaft 14 having its bearings in an upright 15 on the bed plate. The lever 13 is connected by means of a link 16 with a wrist-pin 17 on a cam 18 which is fast on a driven 110

shaft 19 of the machine, whereby the said lever and its attached folder bearing arm 12 are vertically actuated. The arm 12 is held in contact with the cam 18 by means of a retracting spring 20 which is secured to said arm and to an adjustable screw member 21 on the upright 15; the contour of the cam being such as to effect conjointly with the spring, horizontal movement of the folder bearing arm. The resultant of the described vertical and horizontal movements of the folder bearing arm is an approximate figure 8 movement of the folder arm as indicated by the dotted lines in Fig. 10 2 at the right of the mandrel; that is to say, the bar 11 swings inward and upward toward the adjacent side of the mandrel so as to impinge against the lower projecting end flap d^2 of the paper cover and press it 15 firmly toward and against the veneer body, as indicated in Fig. 4; then outward and upward above the upper projecting end flap d' of the cover, as indicated in Fig. 5, and then downward and inward toward the mandrel 20 as indicated in Fig. 6 so as to press such latter end flap against the veneer body and the contiguous cover fold; thence returning 25 to its original position, as shown in Fig. 2.

According to one feature of our invention 30 we provide in close parallel relation to that side of the mandrel contiguous to the overlapping side portions c' of the shuck body, a horizontal pressure bar 22 which bears yieldingly against such side portions 35 during the travel of the shuck along the mandrel toward the final folder for the paper cover; thereby insuring the re-closing of such overlapping portions in the event of their springing outward from the mandrel and assuming the open position illustrated in Fig. 7. In the present instance this bar 22 is supported by an upstanding arm 23 which is pivoted at its lower end to a bracket 24 on a bearing standard 25, said 40 arm being yieldingly drawn toward the mandrel by means of a spring 26 which is secured to the arm and to a bracket 27 on the standard. The inner receiving end 28 of the bar is splayed to permit the ready 45 passage of the laps of the shuck body between the mandrel and the bar.

Another feature of our invention 50 comprises pressure means constructed and operated to apply to the top of the cover, before the final folding of the projecting end flaps thereof, a yielding drawing action toward the folding mechanism, such action tending not only to stretch the paper cover and eliminate excess paste therefrom, but 55 also to remove from the cover any buckle or wrinkle therein due to the opening and subsequent closing of the laps of the shuck body. This body with the partially folded cover thereon is thus firmly held against 60 the top and side of the mandrel, with the 65

projecting end flaps of the cover in position to be efficiently acted upon by the folder bar 11 above-described. In the preferred form of our invention herein illustrated the top pressure means includes a foot comprising a metal plate 29 having an under surface of rubber 30 or other appropriate frictional substance. This pressure foot is secured to the free end of a spring arm 31 which is borne by the upper end of the upstanding arm 32 of a bell-crank lever fulcrumed on a stud on the upright 15. The other arm 33 of the lever overhangs a cam 34 on the shaft 19 and is maintained in contact therewith by a retracting spring 35 which couples the arm 33 to an underlying rocker arm 36 pivotally supported on the shaft 14. The arm 36 extends beneath the cam 34 and is maintained in contact therewith by the action of the spring. The position of the pressure foot relatively to the fulcrum of the bell-crank lever is such that when the lever arm 33 is partially lowered the pressure foot impinges against the top of the shuck cover, and the contour of the cam 34 is such that 70 in one part of its rotation it permits such partial lowering of the pressure foot, and then acts upon and forcibly depresses the underlying rocker arm 36 in such a manner as to augment the tension of the spring and 75 cause the pressure foot to exert additional yielding pressure upon the shuck cover, which pressure, by virtue of the flexible mounting of the foot, effects a motion of the foot transversely of the mandrel and toward 80 the folding mechanism with the result above mentioned. By the arrangement of cam, spring and lever mechanism just described the pressure foot is positively raised by the 85 action of the cam 34 on the lever arm 33 and 90 is yieldingly lowered and transversely moved through the action of the cam on the 95 spring-connected rocker arm 36.

The relative timing of the pressure foot 100 and the folder operating mechanisms is such that while the foot is acting on the paper cover, the folder bar 11 is moving upwardly in contact with the lower flap of the cover.

Preferably the lever arm 31 is provided with a suitably-disposed set screw 37 which bears 110 upon the spring-arm and affords a ready means whereby said arm may be vertically adjusted within limits in respect to the mandrel in order to vary the pressure of the 115 foot on the shuck cover, as need may require.

It is to be understood that our invention 120 is not limited to the specific details of construction herein shown and described, as the mechanism may be modified without departing from the principle of the invention defined in the appended claims.

We claim—

1. The combination with the mandrel and the final cover-folding mechanism of a machine for making paper-covered veneer 130

shucks, of a friction member movable upon and from the top fold of the cover, a spring arm supporting said member, a lever for supporting said arm, and means for positively raising and yieldingly lowering the said lever, whereby the said friction member is caused to exert a transverse drawing action on the cover, said means including a spring and connections whereby the tension 10 of the spring is augmented during the lowering of the said lever.

2. The combination with the mandrel and the final cover-folding mechanism of a machine for making paper-covered veneer

shucks, of a friction member movable upon 15 and from the top fold of the cover, a spring element supporting said member, a bell-crank lever to one arm of which said element is attached, a rock arm below the other arm of the lever, a spring coupling the said 20 rock arm and the adjacent lever arm, and a cam mounted to act upon the coupled arms in opposition to the force of the spring.

Signed at Barberton, in the county of Summit and State of Ohio, this 25th day of 25 August, A. D. 1916.

HENRY C. SCHUMACHER.

WILLIAM A. WINTERS.
